DEER-SCENT VAPORIZER ATTACHMENT FOR A HAND WARMER

Robert W. Smith, Minneapolis, Minn., assignor to Aladdin Manufacturing Company, Minneapolis, Minn., a corporation of Minnesota

Filed Apr. 4, 1960, Ser. No. 60,040

Term of patent 14 years

(Cl. D16—2)

Fig. 1 is a front elevational view of a deer-scent vaporizer attachment for a hand warmer embodying my new design, the broken-line representation of a hand warmer being shown for illustrative purposes only;

Fig. 2 is a right side elevational view thereof;
Fig. 3 is a rear elevational view thereof;

Fig. 4 is a top perspective view taken from the front and left side thereof, the bottom being substantially plain; and

Fig. 5 is an enlarged sectional view taken on the line 5—5 of Fig. 3.

I claim:

The ornamental design for a deer-scent vaporizer attachment for a hand warmer, as shown and described.
